UNITED STATES PATENT OFFICE.

HENRY KINGSFORD HARRIS, OF WESTMINSTER, LONDON, ENGLAND.

ELECTRICAL TRANSMITTING APPARATUS.

1,374,733.

Specification of Letters Patent. Patented Apr. 12, 1921.

Application filed October 17, 1917. Serial No. 197,065.

To all whom it may concern:

Be it known that I, HENRY KINGSFORD HARRIS, a subject of the King of Great Britain and Ireland, residing at 96 Victoria street, Westminster, in the county of London, England, have invented certain new and useful Improvements in Electrical Transmitting Apparatus, of which the following is a specification.

10 This invention relates to electrical transmitting apparatus of the hand set type, manipulated by hand or power for transmitting electrical impulses to an advertising or other device adapted to be set into position by such electrical impulses, and combined, if desired, with automatic means for reversing the direction of movement of the device to be set into position.

The apparatus about to be described, 20 while being applicable to the control of many types of electrical devices is particularly suitable for controlling advertising devices and selectors for advertising devices, that is to say for controlling the position of 25 an advertising part or indicating part directly, or through the intervention of a selector, which can be set either through unit or through both unit and multiple step distances for controlling the position of the 30 indicating part.

The objects of the apparatus are to enable the controlled device to be set into any desired position with great facility and to eliminate the chance of errors when an un- 35 skilled operator is effecting the setting.

The apparatus is adapted for use with an advertising or indicating device in which the part bearing or controlling the indication, for instance a band, is moved in either 40 direction so as to proceed directly from one indication to the next, the calculation of the distance being in that case effected in the transmitting mechanism, and means being provided automatically operated from the 45 transmitting mechanism for causing the part to be set to move in the correct direction, or again the transmitter may be used in combination with a self calculating selector, such for instance as the kinds described 50 in specifications of my former patent, in which case the calculation and direction of setting need not be effected or controlled in the transmitter.

For use with a single and multiple step 55 selector of the character described in my former specifications Ser. Nos. 816,730 and

186,207 I so modify the construction of the transmitter that it is adapted to transmit automatically the proper impulse or impulses for operating the unit step part and 60 the multiple step part or parts in the selector.

The self calculating form of the transmitter comprises a moving member, means controlled by the moving member for transmitting a number of electrical impulses, according to the distance through which the said member is moved, an index on the moving member or on the casing, or adjacent to one of them, adjustable means in connection 70 with the moving member or the casing for determining and limiting the distance through which the said member is to move in proceeding from one setting to the next, and automatic means operated by the moving member such that when in determining a setting, the moving member moves in one direction it causes the device to be set, to move in a certain direction, while when it moves in the opposite direction, the device to 80 be set moves in the reverse direction to that in which it was moving previously.

In a convenient constructional form, the index is provided on a wheel in the casing, a stop or peg is adjusted in position with 85 reference to the index and the stop is brought back against a fixed stop, such as a stop on the casing.

With this form of construction the position of the moving part in the transmitter 90 before each new setting corresponds with the position of the device to be set in the indicating unit or equivalent part and the reversing means comes into operation every time the direction of movement of the moving member in the transmitter is changed.

When the machine is designed for setting one unit at a time a locking device may be provided which locks all the setting movements and enables one to be released at 100 a time, and by the same operation sends an impulse for moving the unit selector switch at the distant station.

An indicator may be provided to show which unit is free for setting, and if desired 105 for preserving a record.

Signal lights or other indications may be added so that the operator may be able to tell when the steps in the cycle of operations at the indicating machine are complete.

Where several units are provided and no

unit switching selector is employed, each unit wheel or the like in the transmitter may be connected to the corresponding unit by the necessary wires.

5 And in order that my said invention may be more clearly understood I will now proceed to describe the same with reference to the drawings accompanying this specification which show by way of example, various forms of hand set apparatus for transmitting electrical impulses.

In the drawing Figure 1 is a sectional end elevation of one form of the apparatus suitable for sending single step impulses. 15 Fig. 2 is a section on the line 2—2 of Fig. 1. Fig. 3 is a detail of the reversing switch and brush carrying bar. Fig. 4 is a front view of a portion of the device. Figs. 5 to 9 show details hereinafter referred to. Fig. 20 10 is an elevation of a modified form of construction of transmitting wheels for transmitting single and multiple step impulses. Fig. 11 is a modified arrangement of the index carrying member. Fig. 11^a is 25 a front elevation with the casing removed, of a recording apparatus suitable for use with the transmitter. Figs. 12 to 16 are diagrams, illustrating systems of working in conjunction with the transmitting apparatus. Fig. 12^a is a detail of the unit setting selector and its magnet.

The same numerals of reference are employed to denote the same parts in all the views.

35 10 is a casing containing a suitable framework in which is mounted a fixed shaft 11. Mounted upon the shaft 11 are a number of wheels 12. Each of these wheels 12 has engraved or otherwise produced on the upper part of the rim, letters or other signs corresponding with the letters or signs which it is desired to set in the exhibiting station.

45 Provided adjacent to each of the letters or other signs is a hole 30 into any one of which a clip, pin or its equivalent may be inserted as hereinafter described.

The lower part of the wheel 12 is provided with a rim 13 having teeth of any 50 suitable form produced thereon.

14 is a rocking arm pivoted at 15 upon a shaft which is common to all the arms for the wheels 12. One end 16 of this arm carries a roller, which is adapted to engage 55 with the teeth on the rim 13. The other end 16^a carries a spring controlled rocking piece which engages with a contact maker 17 which makes contact with the screw 18.

60 Mounted below the end 16 of the rocking arm 14 is a locking cam, 19 provided with a handle 20. The cam surface is so formed that in one position the device locks all the arms against the rims 13 preventing the wheels 12 and the arms 14 from being moved.

Mounted on the axis of the cam 19 is a wheel 21 which is provided with a notch 22 in which a catch 23 under a spring tension is adapted to engage, when the mechanism is in the free position. The wheel 21 carries a pin 24, between which and some fixed portion of the casing is a tension spring 25. The catch 23 is connected by a wire 26 to a trip 27 which is operated by a pin 28 on the snail 29, hereafter more fully described.

70 75 60 is a second notch in the wheel 21 with which a locking catch 61 engages, when the cam 19 is in the locking position. The locking catch 61 is lifted by a spring controlled rod 62, which is provided with a roller 63 which is adapted to be lifted by the flexible shutter 64 when the same is opened for the purpose of working the machine.

80 85 90 95 I will now describe the mechanism for operating the setting wheels 12. 31 is a pin adapted to engage in any one of the holes 30, one pin being of course provided for each wheel 12. 32 are radial arms pivotally mounted on the shaft 11. Two similar arms are provided at the other end of the machine and the outer extremities of the corresponding arms at each end are connected by traverse bars 33 in such a way that as the radial arms 32 are rotated about the shaft 11 the traverse bars 33 are caused to travel over the surfaces of the wheels and to come into contact with any pins which are inserted therein, thus pushing the wheels before them for the remainder of their movement at the same time causing the contact making arm 14 to be operated by the teeth 13.

100 105 110 115 As will be clearly seen in Fig. 1 each time a tooth on the rim 13 passes over the roller 16 on the rocking arm 14, the latter is tilted, causing the spring controlled end 16 to push against the sloping surface on the contact blade 17, bringing the same into contact with the screw 18. As soon as the end of the part 16 passes the end of the 110 sloping surface 17^a the blade 17 is released and the circuit suddenly broken. On the return of the arm 14, the piece 16 is enabled to pass, being tilted upward against the action of its controlling spring.

115 120 125 130 The arms 32 have attached to them links 34 which at their ends are connected to a sliding piece 35. The sliding piece 35 which runs in guides 36 carries a roller 37, conveniently of hide, which runs upon the surface of the snail 29. A section of the slide is shown at Fig. 5. The upper portion of the slide 35 carries a rod 38 having a compression spring around the same and passing through the frame. The snail 29 is fixed to the shaft 11 and also attached to the shaft 11 is the worm wheel 39. Engaging with the worm wheel and carried on a separate shaft 40 is the worm 41. The shaft 40 which passes through the case 10 carries 130

at its outer end a hand winch, 42. This winch 42 on being rotated in a clockwise direction moves the shaft 11 and the snail 29 in the desired direction to operate the 5 setting of the wheels 12. The shaft 40 carries a coiled wire spring 43 one end of which is attached to the supporting frame of the machine and prevents the handle being turned in the wrong direction. When 10 the arms 32 carrying the traverse bars 33 are operated by the mechanism described they bring the two arms simultaneously to a line corresponding to the center of the opening or set position, at the same time 15 turning the respective wheels 12 in the desired directions to transmit the required number of impulses to the exhibiting station.

Referring to Fig. 2 the hub of each of the 20 wheels 12 carries a friction arm 44, only one of which is shown. Each of these arms is held in position by a threaded collar 45 which screws on to the hub and is held by a lock screw. The frictional arm 44 has 25 mounted upon it and passing through it a spring 46 which gives the necessary tension. The outer end of the arm projects between the rims 13 of the wheels 12 which are suitably cut away for this purpose and engages 30 with a reversing switch 47 the construction of which may be clearly seen in Figs. 1 and 2. This comprises an ebonite drum mounted on a shaft common to a number of such switches carrying contact plates as shown 35 in the Fig. 3. Engaging with these contact plates when in the right position are a series of four brushes 48. These brushes are under suitable spring tension and each of them is carried in a metal tube 49 40 mounted in an ebonite bar 50 and having two conducting bars 51 and 52 for connecting two of them to the supply current. The other two are connected by means of 45 terminal screws closing the ends of the tubes to the necessary wires to form the desired circuits according to the system of working.

For convenience in assembling and to enable them to be made larger the switches 50 are arranged in two rows as shown.

With this construction it will be seen that when any one of the wheels 12 is rotated upon the shaft 11, it carries with it the friction arm 44, but that this can only move 55 over a distance of arc corresponding to one tooth in either direction, and it therefore remains in the same position with respect to the switch as that into which it was last set, until the same wheel 12 is moved in 60 the opposite angular direction, whereupon the corresponding friction arm is moved over by the wheel reversing the switch and consequently bringing about the reversal of the current as desired, as will be described

more fully hereafter, in connection with the 65 diagrams.

I provide on the shaft 40 a notched wheel 54. Engaging with this is a locking catch 55 which is pivoted at 56 on the frame. This catch has pivoted thereto a vertical rod 70 57, which extends to the bottom of the casting, and is pressed normally downward by means of a compression spring 58.

The object of this arrangement is to lock the operating handle out of action when the 75 machine is not in use and this may be effected by its engaging the flexible shutter 64 sliding in the slot 59. This shutter is provided with means adapted to lift the rod 57 against the spring 58, when the shutter is moved 80 in to the open position, thus freeing the handle. In Fig. 1 I have indicated the shutter in dotted lines in open position, the wedge 64* which lifts the rod 57 being shown in full lines. This shutter is substantially 85 the same as those in use for the roll top desks. It may be moved from the dotted line position so that the upper portion of the shutter is at the point 200 in Fig. 1. The purpose of the shutter is to prevent tampering 90 with the machine and to keep out the dust.

A second locking catch may be provided, operated by a solenoid from the exhibiting station, in such a way as to lock the transmitting mechanism when the exhibiting units are being set in a manner already described in connection with some of my aforesaid devices, and indicated in one or more of the diagrams accompanying this specification. In Fig. 8, I have shown the modified form of locking mechanism. It consists of an iron clad magnet 110 having attached to its armature 187 a brass push rod 188 carried by its core so as to slide therein and protruding at the back so as to pass through a hole in the arms 189. This arm is hinged in a lug 190 attached to the case of the magnet and passes between the slotted end of another lug 191 which acts as a guide and takes up the side thrust on the arm should the wheel 54 which the arm locks be moved. The rod 188 may carry a compression spring 192 which in the event of the arm 189 not coming exactly opposite a slot in the wheel 110 54 allows the armature and plunger rod 188 to move into the locking position but should the wheel 54 be moved the arm 189 will immediately be forced by the spring into the slot which is brought opposite to it. A compression spring mounted on the back of the rod and sunk within the core of the magnet keeps the same normally in the off position.

I will now describe a device which may be combined with my machine for the purpose of controlling the rest circuits which operate the locking and signaling devices from the indicating station, locking the 125

transmitter and giving an indicating signal, for instance lighting a red light at the transmitting station to show that no more signals must be transmitted or that the transmitter 5 cannot be operated until the setting is effected at the exhibiting station, when the machine is unlocked from the exhibiting station, and another signal, for instance a green light is shown at the transmitting station indicating that the machine can again be operated.

For effecting this purpose, I provide an arm 104, pivoted at 105 to the casing. This arm is under spring control. When the 15 snail 29 is in its normal rest position, the end of this arm rests on the pin 28. In this position an insulated plate which is carried by the arm is pressed against three spring contact studs 106, thus completing the rest circuit. On the other hand when the snail moves forward it causes the pin 28 to allow the arm to drop under the action of its 20 spring breaking the rest circuit until the snail has completed the cycle of operations.

25 When the transmitter has completed its setting cycle, a pin 107 conveniently placed on the arm 32 may cause a bell to be sounded, the pin engaging on its return with a trip spring 108 causing the bell 109 to be struck.

30 In some cases instead of using the contact making arm 14 I may use a plunger, as shown at Fig. 6 which closes the contact for transmitting the impulses. In the form of the wheels 12 shown at Fig. 4 the letters are 35 arranged in order of frequency, with a hole 30 adjacent to each of the letters and there is no casing over the part of the wheels 12 carrying the letters. This form of the rim is more specially suitable for purely mechanical setting.

40 Fig. 7 shows a modified form in which each of the wheels 12 is provided with two sets of holes 30, one hole coming on either side of each letter. In this instance a covering casing is provided shown at 66. This casing is so shaped that one letter and the corresponding holes on each side of it are visible in the central or setting position, while on each side of that position only the 45 holes corresponding to the letters on one side or the other of the setting are visible, as will be clearly seen from the figure.

The object of this arrangement, which is suitable for both hand as well as mechanical 50 setting, is that it is impossible to rotate the wheel 12 too far, as the pin 31 comes up against the shoulder 67 on the casing 66, when in the set position.

55 Referring to Fig. 9, this shows a device which may be used in place of the cam 19 and which may be used for locking the wheels and freeing them in succession, where it is desired to operate over single in place of multiple lines. In this case 70 is a drum 60 mounted upon a suitable axle 71. This

drum is provided with holes 72, which are staggered or come in different positions on the surface. One hole corresponds to each of the contact making devices, such as 14 or the rod shown in Fig. 6 and when the corresponding hole comes beneath its rod 73, the particular contact making movement can be operated, while the others remain locked. It will be noted that the holes on the locking drum are staggered so that only 75 one movement is free at one time.

The drum is rotated by means of pawl 74 engaging with suitable ratchet teeth 75 upon the drum. The pawl is carried by a spring controlled rod provided with a push 80 button 76. In this way the drum can be rotated so as to unlock the movement of each of the wheels 12 in succession.

An indicator may be provided on the 85 drum for showing the operator which of the wheels 12 is free to be operated. This indicator may be of any suitable type. In Fig. 9 I have numbered the teeth of the ratchet. If there are thirty teeth, and consequently thirty units, thirty numbers would 90 be required and there would be thirty corresponding holes in the locking drum. A window such as that indicated at *w* in dotted lines would be provided in the casing, not shown, opposite the number coming at 95 the top, which shows the unit in position.

At the same time by the operation of the drum, a contact maker 77 is operated by means of a second spring controlled blade 78 insulated therefrom and provided with 100 a part which engages ratchet teeth on the drum.

The object of this arrangement is to send an impulse to the switching selector at the exhibiting station for bringing the exhibiting unit corresponding to the next setting 105 wheel into the circuit.

In some cases especially where I use polarized magnets for effecting certain of the operations I find it convenient to employ 110 an earthing switch 79 which makes contact at each step with a separate stud 80 corresponding with the circuit required to be connected for the operation of the particular indicating unit.

115 I will now refer to Fig. 10, which, as previously stated, shows a modified form of construction of transmitting wheel, for transmitting single and multiple step impulses.

120 In this case 81 is the shaft, upon which is mounted, for each transmitter unit, two toothed wheels 82 and 83 the inner wheel 82 being in the present case carried within a recess in the face of the larger one which 125 latter has its teeth cut on the outside of a flange.

The teeth on the inner wheel 82 are so proportioned that in a given amount of arc there are four such teeth 85 as compared 130

with one tooth 86 on the larger wheel. The two wheels 82 and 83 are capable of turning independently of one another excepting so far as this is prevented by the arrangement of pawls hereinafter described. 87 is an arm pivoted at 81 and provided with two pawls. One of these pawls 88 is adapted to engage with the teeth 86 on the wheel 83 and the other pawl 89 is adapted to engage 10 with the teeth 85 on the wheel 82. 90 indicates the outer casing carrying the index letters, and a pointer may be provided in connection with the arm 87 for indicating which of the letters or other symbols is to 15 be set. 91 is an operating handle.

Mounted within the recess of the larger wheel, and engaging with the teeth 85 on the wheel 82 is a spring controlled pawl 92. This pawl is provided at the back with an 20 insulated stud 93 which is adapted when the pawl is lifted to operate the contact making blade 94, which makes contact with the screw 95. The parts 94 and 95 are suitably insulated.

25 Mounted upon the frame is another spring controlled pawl 96 adapted to engage the teeth 86 of the wheel 83. This pawl 96 is provided with an insulating stud 97 which is adapted, when the pawl 96 is lifted to operate the contact making blade 98 and bring the same into contact with the screw 99.

Any suitable means may be provided for preventing the wheels 82 and 83 over running.

30 35 The operation of this form of device will be readily understood.

It is first to be observed that the circuit completed by the blade 98 is the multiple step circuit of a selector, which in this case is set forward four teeth at a time, for instance of the type described in my specifications 816730 and 878,064 while the contact blade 94 sends impulses for setting the selector in the exhibiting unit through single 40 step.

45 In order to render the operation clear, I will consider a specific example.

The arrow 100, at the top of the figure indicates the zero position and it is to be supposed that the selector in the exhibiting unit 50 is to be moved through a distance of 10 teeth, in order to set the required indication.

The required setting will be obtained by sending two multiple step impulses, each 55 equivalent to four teeth and two single tooth impulses.

The handle 91 is moved into such a position that the pointer mounted on the side of the handle comes opposite the indication on the scale 90, corresponding to the 10th indication. This is the position of the parts on 60 the drawing.

When the handle is caused to return, which may be effected in any suitable manner, for instance by means of a device simi- 65

lar to that described in the earlier figures, or by means of a spring and fly governed return, in the first place the pawl 88 moves along the teeth 86, until the forward end of the said pawl comes to the back of the next 70 tooth. No motion of the wheel 83 takes place, but in doing this the pawl 89 being in engagement with a tooth 85 causes the wheel 82 to move through a distance of two teeth thereby sending two impulses at the 75 contact 94 and 95.

The pawl 88 being now in engagement with the tooth 86, as the motion of the arm 87 is continued, the pawl 88 pushes around the wheel 83 until the zero position is 80 reached, that is in the present case the wheel 83 is pushed forward through a distance of two teeth causing two contacts to be made at the blade 98.

It is to be observed that as the wheel 82 is 85 mounted within a wheel 83, and held in position by the pawls 89 and 92 and by a device for preventing over running there is no relative motion now between the wheels 83 and 82, so that no more contacts are made 90 through the blade 94.

Although in the present case I have described an arrangement which is adapted to send the single step impulses first and then the multiple step impulses to the selector, I 95 may where desirable so modify the arrangement of the parts, that the multiple impulses can be sent first, and then the single step impulses.

I may also so modify the construction that 100 a series of single impulses can be transmitted. In this case I should dispense with the multiple step wheel and contact maker and mount the contact making device 94 and its associated pawl, etc., upon the frame.

105 Referring now to Fig. 11 this shows a modified form of the device in which the index 101 is carried by the arm 97. This index is seen through a slot in the casing, and is shown in the zero position ready for setting.

A pin is inserted in one of the holes 102, corresponding to the hole 30 in the first described form of the device. The index carrying member is then pulled around by 115 means of the pin until such pin reaches the zero position indicated by the arrow, when it comes against a stop. At the same time the necessary contacts have of course been made in the manner already described. The 120 letter set is now opposite the zero position acting as a record until the index and arm are returned to zero for a fresh setting. This position is determined by the arm 97 being pushed back to the stop 103.

125 In some cases when I use the index wheels for controlling groups of units having numbers or other indications at the exhibiting station, and it is not required to operate the units in succession at the exhibiting station 130

I may provide upon the outside of the casing, for instance upon the plate 200 (see Figs. 1 and 4) suitable indicating labels or the like for enabling any particular unit at 5 the exhibiting station to be picked out by the operator and operated from the transmitting station. This arrangement would be particularly useful for cricket scoring and like purposes.

10 Referring to Fig. 11^A, which shows a recording apparatus suitable to be combined with the first form of the transmitting apparatus hereinbefore described.

15 Mounted on or moving in unison with the setting wheel 2 or the corresponding set part there is a set of type, letters, signs or symbols which correspond to those on the transmitting wheel 12 or scale or corresponding part and to those on the indicating machine.

20 There is a set of type provided for each wheel 12 or the like corresponding to the letters thereon or set thereby. When the transmitting wheel 12 is set in position by the arms 33 and the pins 31 or whatever 25 means may be employed—a corresponding type character is brought into the printing position 151.

The means by which this printing is effected is now described.

30 152 is a paper sheet or ribbon which may be fed from a roll 153 through suitable guides over the platen roller 154 under the spring clips 155, shown by thick lines and mounted on the platen carrier, and between 35 the platen roller 154 and the jockey roller 156 mounted on the spindle 157 the tension of which is controlled by the spring 158. The platen roller 154 and its accompanying parts are mounted on the pivoted arms 159

40 pivoted at 160 and termed the platen carrier. There being a suitable distance between the arms 159 corresponding to the length of the platen roller and the width of the paper, the pivots being carried on the frame of the 45 machine, which for clearness is not shown. The paper is fed forward at each operation as hereafter described.

45 Mounted on the arm 159 is a roller 161 which bears on a cam wheel 162, mounted 50 on the shaft 11, as before described in reference to the snail wheel 29. The arm 159 in the position shown is held up against the pull of a spring 164 mounted with suitable screw adjustment for regulating the tension 55 on the lug 163 carried by the arm 159 and the pin 165 fixed on the frame. When the cam wheel 162 is rotated at a suitable time the cut away portion 169 is brought to the roller 161 which thus comes into the position 60 shown by the dotted line 184. Thus the arm 159 is lowered suddenly bringing the platen roller 154 carrying the paper 152 into a position where it passes the paper on to the inked type at 151 which has been previously

inked by the ink roller 168. A further 65 movement of the cam brings the rocking arm 159 back into the normal position shown, and at the same time spaces the paper ready for the next printing.

This is effected as follows:—

70 Mounted on and behind the end of the lever 159 and revolving about the same center as the platen roller is an arm 170 controlled by a spring 171 attached to a pin on the arm 159. The lever or arm 170 carries a pawl 172 controlled by a spring 173 and engaging with a ratchet wheel 174 mounted upon the platen roller. 175 is a pin or lug fixed to the frame and engaging with the arm 170 and when the platen carrier arm 159 is in 75 the position shown this pin 175 causes the arm 170 to be rotated forward to its extreme position stretching the spring 171. When the arm 159 lowers the platen as before described on to the type the spring 171 causes 80 the arm as it leaves the pin 175 to draw back the arm 170 carrying the pawl 172 backward over the teeth of the ratchet wheel 174 thus taking up a fresh spacing so that the ratchet wheel and platen are rotated as the arm 90 159 is brought back into its normal position. A pin 176 mounted on the lever platen carrier 159 prevents the ratchet overrunning as the pawl takes up against it at the end of its stroke.

95 The inking of type is effected as follows:—

Pivoted at 166 are two or more arms 167. These carry at one end an ink roller or set 100 of ink rollers 168 and at the other end each arm has a roller 177 engaging with another cam wheel 178 also mounted on the shaft 11 and turning with it. 179 is a spring which causes the roller 177 to be kept against the surface of the cam wheel 178. When the 105 wheel 178 is rotated so that the cam 180 comes beneath the roller 177, the letter is brought into the position shown by the dotted lines 181 and the ink rollers are brought against the type set at 151. To insure more 110 perfect inking of the type I may provide the shaft of the ink rollers with a friction wheel or pinion shown by the dotted line 182, which when the wheel is lowered comes into engagement with the jockey pulley shown by 115 the dotted line 183 mounted on the frame and rotated by the driving mechanism and which may be hung on a spring arm or have a resilient rim, thus the ink wheels may be momentarily rotated against the type. The 120 advantage of the above arrangement is that each type is inked as set.

It will be understood by the above description that the operation is as follows:—

When a printing device is used, the snail 125 29 is shaped so as to complete the movement of the radial arms 32 to the set position in about half its revolution. The cam wheel

178 is arranged relatively to the snail so that it then inks the set type at 151 by bringing the ink wheel into position. Next as soon as the ink wheels have returned to their 5 normal position, the cam wheel 162 is so placed relatively to the others that the platen carrier brings the paper against the inked type. It thus gradually returns to its normal position and the snail 29 completes its 10 operation returning the radial arms to their normal position as before described.

I may vary the construction without departing from the principle. For instance the action might be reversed and the printing effected by the cam movement, which 15 might be positive in both directions or I could use other means than cams. Or the ink roller might merely lie on the type in the ordinary manner or be slightly rotated 20 as it is brought from or returned to the next position so as to present a fresh surface to the type instead of being rotated as before described.

Referring to Fig. 12 which shows a diagram of connection suitable for controlling 25 a system of units by means of a transmitter of the first mentioned type:—

In this figure A is the transmitting station and B is the exhibiting station, the 30 transmitter in this case is of the type shown in Fig. 1 but embodying the modification shown at Fig. 9; the switch 79, has however two series of contacts instead of one.

Referring to the diagram, 70 is the drum 35 for locking the various wheels, 79 is the earthing switch carried thereon and provided with two sets of contacts. 47 is the reversing switch. 17 is the contact blade. 77 is the unit switching contact. 110 is the locking solenoid in the transmitter. 111 and 40 112 are indicating lights. 113 is the rest circuit switch. 114 is the low voltage battery for working the rest circuit. Referring to the exhibiting station B where two 45 units are shown. 115 is the unit switching selector. 116 is the magnet for setting the arm 117 of the same. 118 is a polarized magnet operating the reversing switch 119. 120 is the selector setting magnet for the unit. 50 120^a is the unit setting selector. 121 is the motor. 122 is the locking magnet for locking the drum in the indicating unit, or otherwise locking the driven member. 123 are the contacts connected to the same. 124 is the motor 55 stopping resistance. 125 is the selector. Two sources of transmitting current, S' and S^a are provided in order to prevent any possibility of short circuiting. If only one source, for instance the source S', were pro- 60 vided it might happen that the position of the last set reversing switch 47 was such that the battery might be short circuited by the action of the two switches, namely by the reversing switch 47 connected by the

arm 79 to earth and the contact 77, permanently connected to the same side as the battery. The source S'' is independent of the other. The setting selector 125 (see Fig. 12^a) has a spring barrel 120^b provided with an escapement 120^c operated by the 65 magnet 120. The spring barrel tends to turn in the direction of the arrow and at each impulse the barrel is turned the distance of one tooth. The selector carries a contact ring 120^d engaged by a brush on an 70 arm 120^e. The contact ring has an insulation gap on which the brush rests when the selector is at zero.

The selector being set by the escapement the number of teeth corresponding to the 75 desired letter it is intended to set in the indicating unit, the contact ring has traveled a corresponding distance under the brush. This allows the current to pass through the motor circuit from the local 80 supply when the local current is switched on by the completion of the setting cycle of the unit selector 115, which by a short circuiting plate carried on its arm 117 closes the circuit of a magnetic contact maker through 85 contacts and thus closes the supply circuit to all the motors in the units.

The motor 121 is then driven, the current 90 passing from the positive of the supply through the brush on the selector 125 and 95 the ring, thence to the solenoid magnet 122 and the field of the motor 121, through the armature (in the direction predetermined by the polarity of the setting current) to the selector magnet 120, having passed 100 through the polarized magnet 118; thence back to the negative of the supply.

The motor drives the drum carrying the band or otherwise controlling the indication carrying member; running in unison with 105 the same is the cam. This cam at each half revolution comes in contact with the roller on the arm and causes the spring controlled pawl to rewind the selector 125 one tooth. Thus the selector is rewound one tooth for 110 each indication passed, until when the desired indication is reached, the selector has been wound back to zero. At this moment a stop, not shown, on the selector engages a 115 stop on the frame. A tooth on the escape- ment is cut away, so that it cannot be overwound. The brush has now broken contact with the ring. The current is broken a little before the drum has reached the correct stopping position but the motor circuit, 120 though broken on the selector, is still closed through the contact 123, and the resistance 124 for the locking bolt or catch attached to the movable core or armature of the mag- 125 net 122, when the latter is reenergized con- tinues to close the contacts 123 as it rubs on the drum until the locking catch is able to drop into the slot in the same at the locking

position, when the motor which has been slowed up is stopped.

The unit switching selector 115 is operated by the magnet 116, in the same manner as the magnet 120 actuates the selector 125, namely by a spring barrel 115^a and an escapement 115^b. The spring of the barrel may be wound up by a solenoid in the main circuit of the supply for the motor, or by a small motor in the parallel circuit; or the selector can be positively driven by the magnet 116, in which case it makes a complete circle; but

I prefer the former arrangement as winding to a stop and returning gives security of 15 synchronism.

The operation is as follows:—

The unit locking drum 70 in the transmitting station A is moved one step. This sends an impulse from a second source of 20 supply S'' through the contact 77 along the line 126 through the magnet 116 returning through the earth to the source of supply. This brings the arm 117 in the switching selector to the second contact stud 128. 25 The impulses are then sent by means of the transmitting wheel in the transmitter through the contact 17 to the earth through one circuit on to the arm 79 thence to the earth at the exhibiting station B, through 30 the arm 117 and by the contact stud 128 through the polarized magnet 118, turning it in the direction corresponding with the polarity of the current and operating the switch 119. The current goes through the 35 selector setting magnet 120 returning to the transmitting station by the line 129 through the second circuit on the arm 79 back to the reversing switch 47 and thence to the other pole of the source of supply. In this 40 way the selector at the exhibiting station is set to the required distance and at the same time the switch 119 is thrown over to cause the motor 121 to run in the right direction bringing the next indication into 45 position.

The operation is continued by successively bringing the exhibiting units into circuit as described in my beforementioned previous specifications.

50 When the arm 117 is resting on the first and last contact it brings into operation the rest current from the battery 114 at the transmitting station thereby operating the first contact the signal light 112, as the contact 113 is normally closed when the machine is at rest and also the contact 77^a (which is not shown at Fig. 9 but which is closed when 77 is open) thereby lighting the green lamp 112 and when the contact 55 arm 117 reaches the last contact operating the solenoid 110 and lighting the red lamp 111.

The foregoing system shows a method of controlling a number of units in which the

selectors in the exhibiting station are set in 65 succession, two line wires and an earth being employed for the whole of the units.

In the system shown at Fig. 13 the arrangement is modified in that no unit switching selector is employed at the indicating station B a line wire 130 being employed for each exhibiting unit and the earthing switch 131 only having one series of contacts which are connected to the respective reversing switches 47 of the transmitting unit wheels 12.

When the selectors have all been set the current is switched on over the lines 131 and the exhibiting units are set in position.

In a modified system I may dispense with 80 the earthing switch and introduce a line between the points 132 in the transmitting station and 133 in the exhibiting station, a similar connection being provided for each unit. In this case the transmitting machine 85 may be of the type shown at Fig. 1 and the unit selectors are all operated together.

According to a further modification shown at Fig. 14 the reversing switches 119 at the exhibiting station may be dispensed 90 with, but in this case the motors 121 must have permanent magnetic fields or be separately excited.

Referring to Fig. 15 this shows a system in which a hand set transmitter, such as 95 previously mentioned, is returned to zero electrically by the exhibiting unit as it comes into position.

In this case 134 is the transmitter wheel, having an arm 135 which makes contact on 100 a ring 136, the construction being such that the circuit is broken when the transmitting pointer or the like returns to zero. 47 is the reversing switch, as before described 105 operated by the hand set device as previously described. 118 is the polarized magnet at the indicating station, the other parts being the same as before, except that in this system there is no unit selector. The contact 137 is closed at each step of the setting 110 of the indicating unit.

The working is as follows:—

Supposing the transmitting wheel to be set around through certain distance in the clockwise direction, the reversing switch 47 115 will be moved in the direction to correspond. The current from the source of supply passes through the switch 47 by the arm 135 through the contact plate 134 and through the line 138 through the locking 120 magnet 122 through the motor field, through the armature of the motor by the reversing switch 119 through the polarized magnet 118, operating the same and back to the transmitting station by the line 139. At 125 each step the contact 137 is closed in unison with the movement of the sign carrying member operating the polarized magnet

140, which returns the arm or the like 135 one step toward the zero position. This is repeated at each step until when the arm returns to zero the circuit is broken. The 5 contact 137 is closed at the commencement of each step of the exhibiting unit, thus the indicator will not have completed its setting when the circuit through the line 138 is broken.

10 The locking magnet, however does not break the circuit at the contact 141 until the locking action in the exhibiting station takes place, as the setting position, as described in my application Ser. No. 186,207.

15 Fig. 16 shows a slight modification in which the reversing switch at the transmitting station is connected directly to the armature of a permanent magnet motor, or in place of this a separately excited motor 20 may be employed.

It is to be observed that some of these systems which have the magnetic lock 122 upon the rotating drum at the exhibiting unit can be utilized in connection with a 25 transmitter of the present type without the use of selectors at the indicating station, provided that the step by step motion of the transmitting wheel or equivalent part is arranged to run slower than the rotation 30 of the indicator.

The reversing means for reversing the motor from the control station can also be used for bringing about reversal of the individual units in a system where several 35 units are driven by the same motor with differential gear as described in my former application, Serial No. 186,207, last referred to. In this case the polarized magnet or two ordinary magnets may lock one or 40 other of the differential wheels so as to bring about the driving of the unit in the required direction which being done the selector and a catch on the drum may be employed to hold the necessary wheel locked 45 until the selector has returned to zero and the last movement of the drum or the like is completed.

As has been previously mentioned a transmitting device of the kind described in this 50 specification could be used not only with a selector system but also for working advertising or like apparatus step by step.

In this case each unit setting contact device controlled by the apparatus may be 55 connected to a suitable electric lock which may work in conjunction with a separately driven unit or may be used to lock or unlock a unit movement from a common drive by differential or other gear which may be 60 friction slip gear.

In this way for each contact made by the contact device the magnetic lock will be released and the unit will be thus allowed to move the distance of one indication.

It will also be understood that if the indicating and setting devices are caused to move and the movement of the indicating unit be faster than that of the setting device, so that the magnetic lock is always in the locking position before a fresh contact 70 is made by the contact device, the two devices will work isochronously or synchronously together. For this purpose the driving means of the indicating unit is started or switched on first, and when it has attained the requisite speed, the transmitter is started. This speed can be indicated by an electric lamp or other device on a circuit closed by a centrifugal governor or other appropriate means which may also be employed to lock or free the transmitter. When the desired speed is signified, the transmitter is started and each unit will drive in the direction determined for it by the wiper arm device already described, 85 which is used for working double direction machines and then all the indications will be set step by step with the transmitter unit corresponding to them.

In a simpler device the units can all first 90 be wound back to zero and then wound forward step by step with the transmitter which is then of a similar suitable type.

What I claim and desire to secure by Letters Patent of the United States of 95 America, is:—

1. A transmitting apparatus for operating a sign telegraph or the like, comprising a movable member, means controlled by the movable member for transmitting a number of the electrical impulses according to the distance through which said member is moved, an index associated with said moving member, adjustable means for determining and limiting the distance through which said member is to move in proceeding from one setting position to the next, said adjustable means comprising an adjustable stop associated with the moving member and adapted to be adjusted with 100 reference to the index and arranged to engage a relatively fixed stop, said adjustable means comprising wheels adapted to receive 105 adjustable stop members on their peripheries opposite predetermined signs on said index, and means adapted to engage said index, and means adapted to draw the wheels for drawing them from either side to the setting position.

2. A transmitting apparatus for operating a sign telegraph or the like, comprising 120 a movable member, means controlled by the movable member for transmitting a number of the electrical impulses according to the distance through which said member is moved, an index associated with said moving member, adjustable means for determining and limiting the distance through which said member is to move in proceed-

ing from one setting position to the next, said adjustable means comprising an adjustable stop associated with the moving member and adapted to be adjusted with reference to the index and arranged to engage a relatively fixed stop, said adjustable means comprising wheels adapted to receive adjustable stop members on their peripheries opposite predetermined signs on said index, means adapted to engage said wheels for drawing them from either side to the setting position, and means for locking said wheels simultaneously.

3. A transmitting apparatus for operating a sign telegraph or the like, comprising a movable member, means controlled by the movable member for transmitting a number of the electrical impulses according to the distance through which said member is moved, an index associated with said moving member, adjustable means for determining and limiting the distance through which said member is to move in proceeding from one setting position to the next, said adjustable means comprising an adjustable stop associated with the moving member and adapted to be adjusted with reference to the index and arranged to engage a relatively fixed stop, said adjustable means comprising wheels adapted to receive adjustable stop members on their peripheries opposite predetermined signs on said index, means adapted to engage said wheels for drawing them from either side to the setting position, and means for locking or unlocking said wheels simultaneously.

4. A transmitting apparatus for operating a sign telegraph or the like, comprising a movable member, means controlled by the movable member for transmitting a number of the electrical impulses according to the distance through which said member is moved, an index associated with said moving member, adjustable means for determining and limiting the distance through which said member is to move in proceeding from one setting position to the next, said adjustable means comprising an adjustable stop associated with the moving member and adapted to be adjusted with reference to the index and arranged to engage a relatively fixed stop, said adjustable means comprising wheels adapted to receive adjustable stop members on their peripheries opposite predetermined signs on said index, means for subsequently bringing said wheels to a zero position, and a locking means adapted to lock all the transmitting members simultaneously.

60 5. A transmitting apparatus for operating a sign telegraph or the like, comprising a movable member, means controlled by the movable member for transmitting a number of the electrical impulses according to the distance through which said member is

moved, an index associated with said moving member, adjustable means for determining and limiting the distance through which said member is to move in proceeding from one setting position to the next, said adjustable means comprising an adjustable stop associated with the moving member and adapted to be adjusted with reference to the index and arranged to engage a relatively fixed stop, said adjustable means comprising wheels adapted to receive adjustable stop members on their peripheries opposite predetermined signs on said index, means for subsequently bringing said wheels to a zero position, a locking means adapted to lock all the transmitting members simultaneously, said locking means having associated with it means for automatically returning it to the locking position when the operation of the machine is complete.

6. A transmitting apparatus for operating a sign telegraph or the like, comprising a movable member, means controlled by the movable member for transmitting a number of the electrical impulses according to the distance through which said member is moved, an index associated with said moving member, adjustable means for determining and limiting the distance through which said member is to move in proceeding from one setting position to the next, said adjustable means comprising an adjustable stop associated with the moving member and adapted to be adjusted with reference to the index and arranged to engage a relatively fixed stop, said adjustable means comprising wheels adapted to receive adjustable stop members on their peripheries opposite predetermined signs on said index, means for subsequently bringing said wheels to a zero position, a locking means adapted to lock all the transmitting members simultaneously, a selective switch, and means for operating the selective switch to bring any of the necessary units into circuit.

7. A transmitting apparatus for operating a sign telegraph or the like, comprising a movable member, means controlled by the movable member for transmitting a number of the electrical impulses according to the distance through which said member is moved, an index associated with said moving member, adjustable means for determining and limiting the distance through which said member is to move in proceeding from one setting position to the next, said adjustable means comprising an adjustable stop associated with the moving member and adapted to be adjusted with reference to the index and arranged to engage a relatively fixed stop, said adjustable means comprising wheels adapted to receive adjustable stop members on their peripheries opposite predetermined signs on said index, means for subsequently bringing said wheels to a zero

position, a locking means adapted to lock all the transmitting members simultaneously, a selective switch, means for operating the selective switch to bring any of the necessary units into circuit, and an indicator for indicating the position into which the locking means has been set.

In testimony whereof I affix my signature in presence of two witnesses.

HENRY KINGSFORD HARRIS.
